UNITED STATES PATENT OFFICE.

MICHAEL REEDY, OF MEMPHIS, TENNESSEE.

RAIL-DRILLING MEANS.

1,070,354.

Specification of Letters Patent. Patented Aug. 12, 1913.

Application filed March 17, 1913. Serial No. 754,817.

To all whom it may concern:

Be it known that I, MICHAEL REEDY, citizen of the United States, residing at Memphis, in the county of Shelby and State 5 of Tennessee, have invented new and useful Improvements in Rail-Drilling Means, of which the following is a specification.

My present invention relates to the drilling of transverse apertures in the webs or 10 railway rails, and it seeks the provision of simple, easily applied and efficient means for utilizing to advantage a railway hand car to actuate a drill bit for the purpose stated.

15 The invention in all of its details will be fully understood from the following description and claims when the same are read in connection with the drawings, accompanying and forming part of this specification, 20 in which:

Figure 1 is a fragmentary view, partly in section and partly in elevation, illustrative of the application of my novel devices to a hand car. Fig. 2 is a plan of the same. Fig. 25 3 is a detail section illustrating the manner in which I socket a drill bit in the end of the drive shaft of a hand car and hold the bit to the wheel of the car. Fig. 4 is a detail section illustrative of the manner of mounting the clamping screw comprised in my improvements.

Similar numerals of reference designate corresponding parts in all of the views of the drawings.

35 The hand car illustrated may be and preferably is of the ordinary well known construction in general. Among other elements it comprises a body 1 having a frame bar 2, and also comprises a drive shaft 3 adapted 40 to bear track wheels, one of which is shown in Figs. 1, 2 and 3, and is numbered 4. The shaft 3 may be driven in any approved manner so as to rotate the traction wheels 4 and to propel the car on a railway. In Fig. 45 1 I have shown the shaft 3 as equipped with a pinion 5, and I have also shown a spur gear 6 as intermeshed with the said pinion; the said spur gear being designed to be connected with and actuated by the conventional hand lever ordinarily to be found on hand cars.

50 My invention contemplates supporting one end of the body 1 of the car so as to hold the wheels 4 clear of the track rails when the hand car is to be used for actuating the drill bit as hereinafter described. When the

body 1 is so supported and the hand lever is actuated it will be manifest that the shaft 3 will be rotated at a high rate of speed; also, that at that time the wheels 4 will serve as 60 balance or fly wheels.

In furtherance of my invention I provide in one end of the shaft 3 a socket 7, of angular form in cross-section, and I also provide on the face of the wheel 4 a holder 8 having 65 an angular aperture 9 coincident with the socket 7. The socket and the holder are designed to receive the angular portion of a drill bit 10, and the holder is provided in order to enable the shaft 3 and the wheel 4 70 to powerfully rotate the drill bit 10 about its axis, and this without the necessity of making the socket 7 unduly deep and without the imposition of torsional strain upon the bit. To further hold the bit 10 and pre- 75 clude torsional strain thereof, I provide the wheel 4 with the bracket 11. This bracket 11 is fixed to the face of the wheel 4 and extends a considerable distance laterally outward therefrom, and it is provided at its 80 outer end with a portion 12 in which is an angular bore conforming to and receiving the angular portion of the bit 10. Also in furtherance of my invention, I employ a frame for holding a railway rail in proper 85 relation to the hand car during the drilling of an aperture in the web of the rail. The said frame comprises a bar 13, preferably of wood, arms 14, preferably of metal, pivoted at 15 to the bar 13 and having depressed 90 portions 16 adjacent the bar 13 and also having upwardly reaching portions 17 and terminals 18 extending outwardly from the portions 17, a nut 19, Figs. 2 and 4, mounted in the bar 13, and a clamping screw 20 ex- 95 tending through the bar 13 and the nut 19 and bearing in the latter.

In the practical use of my improved means, the rail 21 to be drilled is supported at a suitable elevation above the road bed 100 of the railway, and the body 1 of the hand car is raised and supported in raised position so as to hold the wheels 4 on the shaft 3 clear of the railway rails. The frame is then positioned as shown in Figs. 1 and 2— 105 i. e., the hooks at the inner ends of the arms 14 are engaged with the car frame, and the bar 13 is positioned at the opposite side of the rail 21, with reference to the car; the rail resting on the arms 14 of the frame. 110 The screw 20 having been turned against the outer side of the rail web, and the drill

bit 10 having been positioned in the socket and holders of the wheel, the hand lever of the car is actuated whereupon the drill bit will be powerfully rotated at a high rate of speed. As the drilling progresses, the screw 20 is turned up and in that way the rail 21 is presented to the drill bit 10 until the transverse aperture is completed through the web of the rail, when the screw 13 is retracted and the rail 21 shifted to proper position for the formation of another aperture.

Subsequently to the boring of apertures in the web of the rail for the connection of 15 fish-plates or for any other purpose, the frame comprising the bar 13 and the arms 14 is removed from the rail and the car frame, and is carried upon the car for subsequent use. The drill bit 10 is also removed from the holding means and placed 20 upon the car, and then the car is lowered to place the traction wheels 4 on the rails, when the car can be moved with the same facility as an ordinary hand car to another 25 point where work is to be done.

It will be gathered from the foregoing that my novel equipment is simple and inexpensive in construction, and that it does not impair the general usefulness of the car.

Having described my invention, what I claim and desire to secure by Letters-Patent, is:

1. In means for the purpose described, the combination of a hand car having a 25 drive-shaft and a traction wheel thereon and also having a socket, of angular form in cross-section, in the socket, a holder fixed to the outer face of the wheel and having an aperture, of angular form in cross-section, coincident with said socket, a bracket 40 fixed to the face of the wheel and having a holder portion in its outer end in which is

an aperture coincident with the first named aperture and said socket, and a frame comprising a bar and arms connected to 45 the bar and having hook portions adapted to be engaged with the frame of the car, a drill for use in the socket and holders, and a clamping screw carried by the bar and adapted to bear against the outer side of a 50 rail, with reference to the drill bit.

2. In means for the purpose described, the combination of a hand car having a drive-shaft and a traction wheel thereon and also having a socket in one end of the drive-shaft, means on the wheel for holding a drill bit, a frame constructed and arranged to be detachably connected with the car and having a portion disposed to be positioned at the opposite side of a rail with reference to 60 the car, a bit adapted to be positioned in the socket and holding means of the shaft and wheel, and a clamping screw mounted in the portion of the frame at the opposite side of the rail to the car.

3. In means for the purpose described, a hand car having a drive-shaft and a traction wheel thereon, drill-bit-holding means on the wheel, a drill bit removably arranged in said means, a frame constructed and arranged to be detachably connected with the car and having a portion disposed to be located at the opposite side of a rail with reference to the car, and means carried by 70 said portion for presenting a rail to the 75 drill bit.

In testimony whereof I have hereunto set my hand in presence of two subscribing witnesses.

MICHAEL REEDY.
